United States Patent

Des. 238,586
Patented Jan. 27, 1976

238,586

ASHTRAY COVER

Robert W. Smith, Mound, and Donald E. Wintz, St. Paul, Minn., assignors to Aladdin Manufacturing Company, Minneapolis, Minn.

Filed July 31, 1974, Ser. No. 493,248

Term of patent 14 years

Int. Cl. D27—03

U.S. Cl. D27—13

FIG. 1

FIG. 2

FIG. 3

FIG. 4

FIG. 5

FIG. 1 is a perspective view of an ashtray cover showing our new design;

FIG. 2 is a top plan view thereof;

FIG. 3 is a bottom plan view thereof;

FIG. 4 is a side elevational view, both sides being identical; and

FIG. 5 is a front elevational view, the rear being identical thereto.

We claim:

The ornamental design of an ashtray cover, as shown and described.
